(57) **CLAIM**

The ornamental design for a sensor housing, as shown and described.

DESCRIPTION

FIG. 1 is an elevational perspective view showing the design for the sensor housing showing our new design;

FIG. 2 is a top elevational view showing the design for the sensor housing;

FIG. 3 is a bottom elevational view showing the design for the sensor housing;

FIG. 4 is a right side elevational view showing the design for the sensor housing;

FIG. 5 is a left side elevational view showing the design for the sensor housing; and,

FIG. 6 is a front end elevational view showing the design for the sensor housing, with the rear end elevational view being identical.

The broken line showing of structural features is included for the purpose of illustrating non claimed subject matter and forms no part of the claimed design.
